CLAIM

The ornamental design for a computer multi-functional control unit, as shown.

DESCRIPTION

FIG. 1 is a perspective view of a computer multi-functional control unit, according to this invention;

FIG. 2 is a front view of the computer multi-functional control unit, as shown in FIG. 1;

FIG. 3 is a side view of the computer multi-functional control unit, as shown in FIG. 1;

FIG. 4 is a side view, opposite the side view shown in FIG. 3, of the computer multi-functional control unit, as shown in FIG. 1;

FIG. 5 is a top view of the computer multi-functional control unit, as shown in FIG. 1;

FIG. 6 is a bottom view of the computer multi-functional control unit, as shown in FIG. 1; and,

FIG. 7 is a rear view of the computer multi-functional control unit, as shown in FIG. 1.
